UNITED STATES PATENT OFFICE.

CHARLES C. NEWBURN, OF CHICAGO, ILLINOIS, ASSIGNOR, BY MESNE ASSIGNMENTS,
TO FRANK B. COOK COMPANY, OF CHICAGO, ILLINOIS, A CORPORATION OF ILLINOIS.

ELECTROMAGNET.

1,103,530.

Specification of Letters Patent. Patented July 14, 1914.

Application filed November 27, 1911. Serial No. 662,648.

To all whom it may concern:

Be it known that I, CHARLES C. NEWBURN, citizen of the United States, residing at Chicago, in the county of Cook and State of Illinois, have invented a certain new and useful Improvement in Electromagnets, of which the following is a full, clear, concise, and exact description, reference being had to the accompanying drawings, forming a part 10 of this specification.

My invention relates to electro-magnetic devices and finds a very important embodiment in electric bells or other electro-magnets in which vibrating armatures are employed, though there are characteristics of my invention which will be of service in other electric devices and I therefore do not wish to limit myself to other electro-magnetic devices that employ vibrating armatures. 20

My invention has for one of its objects the provision of an improved framework for the spool structure of the electro-magnetic device which may readily be assembled with such spool structure, and an electro-magnetic device made in accordance with this feature of my invention includes its spool structure, and a framework between opposite sides of which the spool structure is disposed, and which opposite framework sides are in engagement with the ends of the spool structure, each spool structure end and the framework side engaging the same being of formation to enable the spool structure and the sides of the framework between which it is disposed to be slid into engagement, in the assembly of the parts, thereby to position the spool structure in the framework. 30

Another feature of my invention relates to those electro-magnetic devices which employ spools in pairs and which spools operate to supply a magnetic circuit common thereto with flux. It is the object of this feature of my invention to eliminate the screws which have hitherto been employed for uniting the heel pieces of the electro-magnets with the cores of their spools and by this feature of my invention I improve the mechanical assembly of the spools of an electro-magnet and the cores of such spools. 40 An electro-magnetic device made in accordance with the preferred embodiment of the present feature of my invention includes a pair of spools and cores therefor each having magnetizable portions terminating ad- 50

jacent the heads of its spools and both having additional separately formed magnetizable portions that are integral parts of a single piece of magnetizable core making material and which additional separately formed portions are disposed with in the spools and are in extended contact with the complementary core portions within the spools. I do not desire to have my invention limited to a common core portion of 60 magnetizable material. 65

My invention has for another of its objects the provision of an electro-magnet having an oscillating armature and a spring for swinging the armature in one direction, 70 the spring taking part in positioning the armature in a support that is supplied in addition to the spring. An electro-magnet embodying this feature of my invention may generally be described as one which includes 75 an oscillating armature structure, a support for the armature structure and upon which said armature structure may oscillate, and a spring supplied in addition to said support for swinging the armature structure in one 80 direction and operating to hold the armature structure in engagement with its support. 85

I will explain my invention more fully by reference to the accompanying drawing 85 showing the preferred embodiment thereof and in which—

Figure 1 is a view in elevation, partially in section, of a bell structure embodying the different features of my invention; Fig. 2 90 is a sectional view on line 2 2 of Fig. 1; Fig. 3 is a sectional view on line 3 3 of Fig. 1; Fig. 4 is a sectional view on line 4 4 of Fig. 5; Fig. 5 is a sectional view on line 5 5 of Fig. 1; Fig. 6 is a view in perspective illustrating some of the structural characteristics; Fig. 7 is a detail view of a portion of the framework; and Fig. 8 is a plan view of the fragment shown in Fig. 7. 95

Like parts are indicated by similar characters of reference throughout the different figures. 100

As I have embodied the invention, it includes two spools 1 1 each having a core formed of a plurality of parts, these parts 105 desirably being in the form of laminæ. Laminæ 2 comprising a part of each of the cores terminate adjacent the ends or heads of the spools. Each core includes a separate additional lamina 3, the laminæ 3 form- 110

ing integral parts of a single strip of magnetizable material, these laminae 3 being thus merged at two of the adjacent ends of the spools and thus terminating adjacent the 5 opposite ends of the spools. The integral laminae 3 are in extended contact with the balance of the cores formed of the laminae 2 throughout the interior of the spool bores so that firm mechanical union is established 10 between the two cores of the adjacent spools. When the laminae 3 are made of magnetizable material, the intimate contact that is afforded between the same and the balance of the core portions serves to cause all of 15 the laminae within each spool bore to be well included in the same magnetic circuit, the integral portion 4 uniting the laminae portions 3 serving to join the cores in a well established magnetic circuit. Hitherto the 20 cores of the spools were joined in the same magnetic circuit by means of heel pieces that were held in contact with the cores by means of screws, a construction that gave rise to much magnetic reluctance at the 25 screws, a defect which the structure of my invention overcomes.

The free poles of the composite core which I have supplied for the two spools face the armature structure 5, this armature 30 structure including a leaf extension 6 that terminates in a tongue 7 which is received in the groove 8 of the armature support 9, this armature support having lateral extensions 10 for the purpose of confining the 35 armature to its proper plane of movement. A leaf spring 11 is supplied, in addition to the armature support, for the purpose of swinging the armature in one direction, the magnet operating to swing the armature in 40 the reverse direction. This leaf spring, which is provided in addition to the armature support 9, serves to bottom the tongue 7 in the groove that receives it whereby the armature and its mounting are held in engagement; the spring 11 thus having a new 45 function added to it. The type of bell shown is a direct current bell including contacts 12 and 13 that are brought into engagement by the spring 11 when the magnet 50 is deenergized and which serve, when engaged, to close circuit through the spools for the purpose of attracting the armature in opposition to the spring 11. I do not wish to be limited, however, to the embodiment 55 of my invention in direct current bell structures. The spring 11 may be anchored in any suitable way at the end opposite to that end which is connected with the armature. I have shown a screw 14 whose stem 60 has been threaded through an opening in the spring 11 and which stem has an annular groove cut therein adjacent the screw head to receive the spring. The tension of the spring may be determined by turning

the screw and the tension which has been 65 thus secured may be maintained by means of a lock nut 15.

The remaining feature of my invention resides in the provision of a framework for the spool structure of an electro-magnet irrespective of the purpose to which such electro-magnet is put. In practising this feature of my invention the opposite sides 70 16 17 of the framework are slid into engagement with the ends of the spool structure 75 (which spool structure may contain one or more spools) the core portion of the spool structure desirably projecting beyond the spool structure and being slid into engagement with the sides 16 and 17 of the framework 80 whereby the spool structure is positioned within the frame work. The sides 16 and 17 of the framework are provided with apertures that receive the projecting core ends of the spool structure but I do not 85 wish to be limited to the formation of the framework and spool structure that enables the spool structure and framework to be slid into engagement when parts are being assembled. As I have preferably embodied 90 the invention, the framework side 17 is separately formed from the balance of the framework and when thus separately formed it is 95 preferably provided at one end with means whereby it may have hook engagement with an adjacent portion of the framework, the framework side 17 being illustrated with a hook 18 that is adapted to engage an offset rib 19 struck up from the portion of the framework adjacent to the hook 18, this 100 hook and rib being initially engaged whereafter the other end of the framework side 17 is held in engagement with an adjacent framework portion by means of a screw 20. The screw 20 is a convenient means for uniting an end of the framework side 17 with an adjacent portion of the framework, but 105 I do not wish to be limited thereto.

The framework side 17 is provided with 110 apertures 21 through which the core ends of the spool structure may project into proximity with the armature 5. Where the framework is in electrical connection with a terminal of the spool winding, a twin washer 115 22 surrounds the core ends that project through the openings 21 and insulate the framework side 17 from the plate 23 that is secured to the spool structure as indicated in Figs. 1, 3 and 4 and which plate is provided with an arm extension 24 that constitutes a support for the back contact 13.

While I have herein shown and particularly described the preferred embodiment of my invention, I do not wish to be limited to the precise details of construction shown 120 and particularly described as changes may readily be made without departing from the spirit of my invention.

Having thus described my invention, I claim as new and desire to secure by Letters Patent the following:—

1. An electro-magnetic device including a spool structure whose ends are provided with projections; a frame work portion having three sides, the intermediate one of which is recessed to receive and have sliding relation with the projecting formation at one end of the spool structure; a framework portion constituting a fourth side of the frame work and recessed to receive and have sliding relation with the projecting formation at the other end of the spool structure, there being hook connection between one end of this fourth side and an outer one of the three sides of the first aforesaid framework portion; and a screw joining the remaining outer side of the three sided framework portion with the remaining end of the fourth side of the framework.
2. An electro-magnetic device including a spool structure whose ends are provided with projections; a framework portion hav-

ing three sides, the intermediate one of which is recessed to receive and have sliding relation with the projecting formation at one end of the spool structure; a framework portion constituting a fourth side of the framework and recessed to receive and have sliding relation with the projecting formation at the other end of the spool structure, there being hook connection between one end of this fourth side and an outer one of the three sides of the first aforesaid framework portion; and a fastening device joining the remaining outer side of the three sided framework portion with the remaining end of the fourth side of the framework.

In witness whereof, I hereunto subscribe my name this 18th day of November A. D., 1911.

CHARLES C. NEWBURN.
